POWER SHIFT MECHANISM FOR KEYBOARD
PERFORATORS AND COUNTERSTheodore I. Przysiecki, Park Ridge, Ill., assignor
to Teletypesetter Corporation, Chicago, Ill., a
corporation of Delaware

Application August 25, 1949, Serial No. 112,222

5 Claims. (Cl. 164—112)

1

This invention relates to composing systems and apparatus therefor and particularly to improvements in perforators and counters which may be utilized for preparing a perforated strip for the automatic control of composing machines.

The primary object of the present invention is to enhance the operativeness of a keyboard perforator and counter.

Another object of the invention is to provide a power operated shift and unshift mechanism for keyboard devices.

A further object is to provide a positive means for shifting the counting code magazine of a keyboard perforator and counter.

Composing machines of the linecasting type are provided with matrices consisting of small brass units carrying indented characters in their edges, which are of different thicknesses due to the fact that the characters vary in width. To produce lines of type, the matrices are assembled into a line of predetermined definite length before the casting operation is performed, the number of matrices necessary to complete a line varying with the particular matrices already assembled. The length of the line, therefore, is dependent upon the thickness of the several characters or matrices comprising the line.

It is necessary, during the preparation of a control strip representing lines of composed matter for the production of the slugs or lines of type, to totalize the various thicknesses of matrices so that the operator will be apprised of the length of line remaining available as each key is operated, and can judge the justifiability of the line. Shift and unshift operations are required to enable proper counting operations to be performed in the upper and lower cases.

To achieve the above and other objects of the invention, the keyboard perforator and counter, according to U. S. Patent No. 2,059,250 issued to H. L. Krum is modified to embody the features of the present invention. In addition to the Krum patent, reference should also be had to U. S. Patent No. 2,080,424, granted May 18, 1937, and U. S. Patent No. 2,083,570, granted June 15, 1937, to E. S. Larson et al. and E. S. Larson, respectively, for a full and comprehensive disclosure of a keyboard perforator and counter in which the features may be embodied. These patents are incorporated by reference into this specification.

In accordance with the present embodiment of the invention, the keyboard includes key levers, arranged in a manner characteristic of type-

2

writers, which operate through a permutation selector mechanism contained in the housing of the perforator and counter apparatus, to position permutably a series of code discs of a selector to select one of a circumferentially arranged series of rods. A counting barrel or rotor, to which a continuous torque is imparted, is provided with a circumferentially arranged series of slides, an operated one of which cooperates with the selected rods to determine the degree of rotation of the counting barrel. Thus, as the counting barrel is rotated through variable angles according to the rod selected, like rotation is imparted to a spiral gear operatively associated with the counting barrel. Through a suitable gear train, variable motion is imparted to a matrix pointer associated with an indicator dial.

As the keys are depressed, the matrix pointer will be moved through various cumulative distances corresponding to the widths or thicknesses of the matrices represented by the keys. The variable motion imparted to the matrix pointer may be adjusted for different fonts of type by interposing between the key levers and the selector mechanism for the counting device an interchangeable code bar unit comprising a plurality of pairs of elements, one pair allotted to each key lever and operable thereby. Means is provided for shifting the counting code bar unit from its lower case to upper case positions and vice versa by a power operated shift device under the control of the shift and unshift key levers respectively, and also to provide means for insuring the prompt return of the matrix pointer to its beginning-of-line position during a single revolution of the operating clutch release mechanism.

A more comprehensive understanding of the present invention may be had from the following description, taken in conjunction with the accompanying drawings, wherein like reference characters represent similar parts throughout the several views.

In the drawings,

Fig. 1 is a perspective view of a perforator and counter with parts broken away showing the apparatus necessary for an understanding of the present invention;

Fig. 2 is a perspective view of the mechanism for carrying out the present invention; and

Fig. 3 is a cross sectional view showing the shift mechanism according to the present invention.

Having reference to Fig. 1 it is noted that most of the parts shown have their counterpart in the structure illustrated in U. S. Patent No. 2,059,250,

the entire perforating mechanism not being shown, but which, nevertheless, is operatively a part of the present invention. In Fig. 1 a plurality of key levers 11 are pivoted on a common rod (not shown) and are normally held in horizontal position by individual springs (not shown). These key levers extend over a number of pairs of selector bars 12 and 13 included in the perforator selector unit indicated generally by the numeral 14, and the pairs of bars 15 and 16 (Fig. 3) included in the selecting unit of the counting mechanism indicated generally as 17. Each key lever 11 is arranged to depress one of the bars 12-13 or 15-16 of each pair of bars. Through the medium of rocker arms 18, the bar 12 or 13 lifts the other bar of the pair and reciprocates longitudinally a bar 19 cooperatively associated with and subjacently disposed to each pair of bars 12 and 13 to impart corresponding movement to the associated pivoted member 21. The members 21, as disclosed in said patent, control the operation of punch interference elements 22 in the tape perforating unit 23. Bars 19 are set in characteristic combinations, and for this purpose, bars 12 and 13 are provided with notched upper edges, the bars of each pair being complements; that is, the high portions of one bar are disposed opposite the low portions of the other bar of the same general pair.

Interposed between the series of key levers 11 and the counter selector unit 17 is a removable and interchangeable code bar unit, indicated generally by the numeral 24, which carries therein a plurality of pairs of coded elements 25. In this manner, there is allotted to each of the key levers 11 a pair of coded elements 25 which coact with the pairs of permutation bars 15 and 16 of the counter selecting unit 17.

The removable code bar unit 24 for carrying the pairs of coded elements 25 comprises a channel-shaped member having a webbed portion 26 and side walls 27 and 28, which are, in turn, provided with flanges 29 and 31, respectively (Fig. 3). The web 26 is provided with rectangular apertures 32 (Fig. 1) to guide the vertical projections 33 and 34 of the coded elements 25. The flanges 29 and 31 have notches in vertical alignment with the apertures 32 to insure the vertically guided movement of the coded elements 25.

The coded elements 25 are retained in their uppermost positions by individual retention springs 35, each of which, as indicated in Fig. 3, comprises a coil spring having its extremity extended tangentially thereto and oppositely directed therefrom, which, in turn, terminates in laterally disposed portions 36 adapted to coact with the inner surface, respectively, of projections 33 and 34 of the coded elements 25. These springs 35 are mounted upon a rod 37 carried in the unit 24. A guide member 38 guides the extremities of the springs 35.

A shiftable carrier or cradle, indicated generally by the numeral 41, controls the movement of the removable code bar unit 24 from the unshift or front position (exemplified by the dot-and-dash lines 40 in Fig. 3) to the shift or rear position, and vice versa. Carrier 41 consists of a framework comprising a pair of channeled guides 42 and 43, suitably spaced apart to provide guideways for the insertion and removal of code bar unit 24. As shown in Fig. 3, the carrier 41 is mounted at its four corners on corner posts 44 which, in turn, are supported upon links 45, pivotally connected to the posts 44 and brackets 46, mounted on base portion 47. The shifting of

carrier 41 is accomplished in parallel motion manner by shift mechanism which, according to the present invention, is controlled by the shift key lever 48 and unshift key lever 49 (Fig. 1) through power means to be presently described.

In order to associate the proper projections 58 on the counting code elements 25 with the proper counting selector bars 15 and 16, it is necessary to shift the position of the code bar unit 24 from right to left, or vice versa, as viewed in Fig. 3, which is from front to rear, or vice versa, of the keyboard apparatus. This movement is accomplished, as previously indicated, by means of the shift and unshift key levers 48 and 49, having reference to Fig. 1. When any key lever 11 is depressed, the selector bars 15 and 16 will be moved in accordance with the location of the projections 58 on the code elements 25 to cause the movement of the permutation bars 59 (which are operatively associated with the pairs of selector bars 15 and 16 in a manner similar to the association of bars 19 with the selector bars 12 and 13) in various permutations. As indicated in Fig. 3, the code projections 58 on one of the elements 25 are effective in one position, and the projections 58 on the other element 25 of the pair are effective in another position. The carrier 41 is shown in Fig. 3 in its right-hand or unshift position, in which position, the projections 58 of the rear element 25 are observed as being in cooperative relation with the selector bars 15 or 16. In the position shown, the projections 58 of the front element 25 are observed as being out of cooperative relation with bars 15 and 16. When the carrier 41 is moved to the shift or leftward position, the projections 58 on the front element 25 will be disposed in cooperative relation with the bars 15 or 16, and the projections of the rear element 25 will be out of cooperative relation with bars 15 and 16.

The bars 59, Fig. 3, as fully described in said Patent No. 2,059,250, are operatively connected to a corresponding series of Y-shaped members 61 (Fig. 1) which are adapted to be positioned in accordance with the operation of the permutation bars 59 to control the setting of a plurality of notched discs 62, forming part of a code disc selector, indicated generally by the numeral 63. Individual to each of the members 61 and notched code discs 62 is a transfer lever 64, which is pivotally mounted on a rod 65 carried in a bracket (not shown) operated in a manner described in said Patent No. 2,059,250, to reciprocate the transfer levers vertically. Upon reciprocation, the transfer levers 64 will be moved into cooperative relation with the Y-shaped members 61; that is, whether the members 61 are swung to the right or left, as viewed in Fig. 1, the abutments 60 of the transfer levers 64 will engage or be free of one or the other of the abutments 70 on the upper end of Y-shaped members 61 to cause the discs 62 to be rocked in either a clockwise or a counter-clockwise direction. With the Y-shaped members 61 operated in varying permutations in accordance with the movement of the permutation bars 59, the disc 62 will likewise be rotated in varying permutations and will, for each permutation, cause an alignment of notches formed in the periphery of the discs.

Cooperating with the notches in the discs 62 are a plurality of rods 66 arranged with anti-friction rollers 67, there being a rod individual to each set of aligned notches. Each of the rods 66 is centripetally biased by the garter spring 68. In this manner, the rods 66 tend to move radially

toward a common center into the notches of the disc 62, but inasmuch as the notches are arranged so that for each setting of the discs, only one group of notches will be in transverse alignment, only one of the rods 66 for each selection will move into the notches. Also, the notches in the discs 62 are arranged so that when the discs are moved for a subsequent selection, the previously selected rod 66 will be cammed outwardly against the action of the spring 68. Carried on the right-hand end of each of the rods 66 is a stop member 69 (Fig. 1) which slides in slots formed in a circular member 71.

To the right of the code disc selector 63 (as viewed in Fig. 1) is a counting barrel or rotor 72 forming part of the counting mechanism, which is rotated by power communicated from a continuously rotating motor (not shown), through a friction clutch 73. The counting unit 72 comprises a plurality of circumferentially arranged slides 74, which are longitudinally slidable and adapted to coact with the stop members 69 to determine the degree of rotation of unit 72, and any of the slides 74 which are found in the zero position are operated invariably by a lever (not shown), while a previously operated slide is simultaneously restored to its normal or nonoperated position by a collar 75 to accomplish, through the coaction of an operated slide 74 and a selected stop member 69, the incrementally progressive movement of the counting unit 72. The counting unit 72 includes a shaft 76 on which is formed a worm 77.

As previously mentioned, the slides 74 cooperate with the rods 69 to arrest the rotation of the counting unit 72, which is driven, through friction clutch 73, to cause a corresponding degree of rotation to worm 77. The rotation of the worm 77, which meshes with a gear 78 secured to a shaft 79, causes the correspondingly angular rotation of a shaft 81, through gears 82 and 83. Shaft 81 imparts rotation, through a means fully disclosed in said Patent No. 2,059,250 and illustrated in Fig. 15 of said patent, to the matrix pointer 86 (shaft 81 being comparable to shaft 212 of said patented disclosure).

As shown in Fig. 1, the indicator comprises a bracket 87, which carries pivotally thereon, through the instrumentality of member 100, a dial 88, which is provided adjacent to its outer arcuate edge with a scale or series of graduations representing increments of a maximum length of line. The reverted end of a matrix pointer 86 moves along this edge of the dial from left to right, towards zero, in response to the totalization of the matrix thicknesses by the counting mechanism. Thus, the distance from the pointer 86 to zero indicates the amount of space left in the line to be filled with matrices if the line contains no space bands. However, if space bands are inserted in the line, the space remaining to be filled varies with the number of space bands inserted. Consequently, to indicate the justifiability of the composed line, a pair of space band pointers 89 and 91 are provided, the distance between the pointers 89 and 91 indicating the amount of expansibility of the space bands. In the embodiment shown, the dial 88 is articulated to the minimum space band pointer 91, through a pin 92, and is movable with said pointer. The space left in the line to be filled when space bands are inserted is represented by the distance between the matrix pointer 86 and any point between space band pointers 89 and 91. The manner of effecting the differential or proportional movement of pointers 89 and 91 toward the left

(from their zero position) is fully set forth in said Patent No. 2,059,250. The return of the indicating mechanism to the beginning-of-line position is effected in the manner disclosed in said Patent No. 2,059,250 by operating a clutch 100 carried on a shaft 101.

Having reference to Figs. 1 and 2, a bar 102 is provided which is similar to bar 291 of the structure shown in said Patent No. 2,059,250. Like said bar 291, the bar 102 is slidably mounted for reciprocable movement and is connected pivotally at one end to the downwardly directed arm of bell crank lever 103 (similar to bell crank lever 295 of said patent) pivotally supported on a pivot shaft 104. Bell crank lever 103 is operated by a cam (not shown) carried on shaft 101, in the manner described in said Patent No. 2,059,250.

As shown in Fig. 2, the reciprocating bar 102 carries at its end, opposite to the bell crank 103, a pair of attrahently biased pawls or interponents 105 and 106 which are mounted pivotally on pivot stud 107 secured to the bar 102. Interponents 105 and 106 are biased attrahently, or toward each other, by a spring 108, to cooperate with mechanism hereinafter described, controlled by the shift key lever 48 and the unshift key lever 49, to shift the carrier or cradle 41. The shifting movement is accomplished in the following manner. Suitably carried in the portion 47 are bell cranks 51 and 52 pivoted at 53 and 54, respectively. The horizontal arms of bell cranks 51 and 52 are adapted to coact with shift and unshift key levers 48 and 49, and the depending arms of bell cranks 51 and 52 are pivotally connected to a bar 55 which is slidably carried in the portion 47. Bar 55 is provided at its right end with a stud 56 by means of which bar 55 is pivotally articulated to the depending arm of a bell crank lever 57 pivotally supported on a pivot stud 50 mounted on a bracket 59 secured to the base portion 161.

The horizontal arm of bell crank 57 is connected pivotally by means of stud 162 to one arm of a lever 163 pivotally mounted on a pivot 164 carried in the bracket 59. Lever 57 is provided with a hole 165 to clear the pivot 164. Lever 57 is also provided with a V-shaped end which cooperates with a spring detent member 166. The other arm of lever 163 terminates in a laterally directed portion 167 having a bifurcated extremity adapted to cooperate with the free ends of the interponents 105 and 106.

When the unshift key lever 49 is depressed the bell crank lever 52 is rotated in a clockwise direction, and the bar 55 is actuated leftwardly (as viewed in Fig. 2), thereby imparting clockwise rotation to the bell crank lever 57. Through its pivotal connection 162 with lever 163, the latter lever is rocked clockwise to cause its lateral portion 167 to press interponent 106 downwardly against the action of spring 168. Spring 108 thereby biases the companion interponent 105 clockwise to cause interponent 105 to bear against a lever arm 169 of a U-shaped lever 169, and to bring the tooth 171 on said interponent 105 into operative engagement with said lever arm 168. Then upon the cyclic reciprocation of bar 102, the pawl or interponent 105 is first actuated leftwardly (as viewed in Fig. 2), whereby tooth 171 imparts, through arm 168, clockwise rotation to lever 169 against the action of its spring 170. During this movement of bar 102, the interponent 106 is held out of operative engagement with its respective operating lever 172 by the lateral portion 167 of lever 163.

Lever 169 is mounted pivotally on the pivot shaft 173, and its arm 174 terminates in a vertical portion carrying an abutting screw or cooperater 175 which cooperates with a lateral projection 176 on the upper arm of a lever 177 mounted on a pivot 178. The lower arm of lever 177 terminates in a bifurcation which straddles a pivot stud 179 carried on a projection 181 integrally associated with the cradle 41. The projection 181 and stud 179 thereby form a coupling 10 instrumentalities between lever 177 and cradle 41. Thus, when clockwise rotation is imparted to lever 169 by interponent 105, as previously described, the abutting screw 175 acts through the projection 176 to rotate the lever 177 clockwise about the pivot 178. In this manner the cradle 41 is shifted from the full line position shown in Fig. 3 to the position exemplified by the dot and dash line 40, thereby presenting a different arrangement of wards or code projections 58 to the selector bars 15 and 16.

When the shift lever 48 is depressed, the bell crank lever 51 is rotated in a counterclockwise direction, and the bar 55 is actuated rightwardly, thereby imparting counterclockwise rotation to the bell crank lever 57. Through the pivotal connection 162, counterclockwise rotation is also imparted to lever 163 to cause the bifurcated end of lateral portion 167 to lift the interponent 106 upwardly against the action of spring 108 thereby by removing tooth 171 from operative relation with lever arm 168. Spring 108 at the same time biases the interponent 106 counterclockwise to cause said interponent to bear against the lever 172 thereby bringing the tooth 183 into operative relation with said lever 172. Then, in response to the cyclic reciprocation of bar 102, the pawl or interponent 106 is first actuated leftwardly, whereby the tooth 183 imparts clockwise rotation to the lever 172 about its pivot 184.

Lever 172 cooperates with an arm 185 of a U-shaped lever 186 mounted pivotally on said pivot 173, and normally biased clockwise by a spring 187. Arm 188 of lever 186 terminates in a vertical portion carrying an abutting screw or cooperater 189 which, like screw 175, cooperates with the lateral projection 176 on the upper arm of lever 177. Thus, when clockwise rotation is imparted to lever 172 by interponent 106, as previously described, the lever 186 is rotated counterclockwise through the coaction of lever 172 and lever arm 185. When the lever 186 is thus rotated counterclockwise, it will cause, through abutting screw 189, counterclockwise rotation to be imparted to the lever 177 about the pivot 178. In this manner, the cradle 41 is shifted from the leftward position, exemplified by the dot and dash line 40 (Fig. 3), to the full line position (or rightward) position shown, thereby changing the relative positions of coded projections 58 and the selector bars 58.

Having reference to Fig. 1, lever 177 terminates at its upper end in a bifurcation adapted to cooperate with a pivot stud 191 carried on the depending arm of a U-shaped lever 192 supported pivotally on a pivot shaft 193. In this manner, lever 177 is pivotally articulated to the lever 192. A spring 194 normally biases the lever 193 in a counterclockwise direction. Connected pivotally to the horizontal arm of lever 193 is one end of a link 195, the other end of which is connected pivotally to the rightwardly directed arm of a lever 196 suitably pivoted on a pivot shaft 197. The leftwardly directed arm of the lever 196 carries at its extremity a target 198 which has

5 on its front face or surface colorations indicative of the position of the cradle 41. In the particular embodiment shown, the target 198 is visible through an opening 199 formed in the dial 201 and serves to indicate to the operator by means of colors the position of the cradle 41 and hence the code bar unit 24.

Although the present invention has been disclosed in connection with the perforator and counter, it is of course, understood that the invention is capable of embodiment in many and varied applications other than that specifically disclosed without departure from the spirit and scope of the invention as defined in the appended claims.

What is claimed is:

1. In a keyboard apparatus, a series of keys comprising character keys and shift and unshift keys, a counting mechanism comprising means to totalize various additive amounts and to indicate continuously such totalizations, counting controlling means controlling the counting mechanism, a unit carrying a plurality of coded elements to control counting, parallel motion means for supporting said unit provided with a coupling instrumentalities, means cooperating with said instrumentalities to effect shifting of said unit, a pair of bell crank levers having confronting cooperators cooperable with said means, a pair of attrahently biased interponents having confronting teeth cooperable alternately with said bell crank levers, a power means a cyclically reciprocable member operated by said power means for operating said interponents, cam means for operating said member, and shift and unshift key means for determining the coaction between said interponents and said bell crank levers, whereby said parallel motion means is shifted to either of two positions.

2. In a keyboard apparatus, a series of keys, a counting mechanism comprising means to totalize various additive amounts and to indicate continuously such totalizations, a unit carrying a plurality of coded elements for controlling said counting mechanism, parallel motion means for supporting said unit, means for shifting said parallel motion means to either of two positions, a pair of means having confronting cooperators cooperable with said shifting means, a power operated reciprocating means comprising a pair of attrahently biased interponents having confronting teeth cooperable alternately with said pair of means, and key controlled means for determining the coaction between said interponents and said pair of means, whereby the effectiveness of said shifting means is determined.

3. In a keyboard apparatus, a series of keys, mechanism to be operated, a unit carrying a plurality of coded elements for controlling said mechanism, means for supporting said unit, means for shifting said supporting means to either of two positions, a pair of means cooperable with said shifting means, a power operated reciprocating means comprising a pair of interponents normally biased toward each other, said interponents having elements cooperable alternatively with said pair of means, and means controlled by said keys for determining the coaction between said interponents and said pair of means.

4. In a keyboard apparatus, a series of keys, mechanism to be operated, a unit carrying a plurality of coded elements for controlling said mechanism, means for supporting said unit, parallel motion means for shifting said supporting means

to either of two positions, a pair of means cooperable with said shifting means, a power operated reciprocating means comprising a pair of interponents normally biased toward each other, said interponents having elements cooperable alternatively with said pair of means, and means controlled by certain of said keys for determining the coaction between said interponents and said pair of means, whereby the effectiveness of said parallel motion means is determined.

5. In a keyboard apparatus, a series of keys, mechanism to be operated, a unit carrying a plurality of coded elements for controlling said mechanism, pivoted carrier means for supporting said unit, operating means comprising a pair of means for pivoting said carrier means to determine the shift or unshift position of said unit, said pivoting

means comprising a power operated reciprocating means including a pair of interponents normally biased toward each other and having elements cooperable alternatively with said pair of means, and means controlled by certain of said keys for determining the coaction between said interponents and said pair of means.
